UNITED STATES PATENT OFFICE.

WALTHER KIBY, OF NOORDWIJK AAN ZEE, NETHERLANDS, ASSIGNOR TO JOHAN CHRISTIAAN BARON VAN HAERSOLTE VAN HAERST, OF DRIEBERGEN, NETHERLANDS.

CONSTRUCTION OF SUBHEATED REGENERATIVE COKE OVENS.

Application filed July 13, 1920. Serial No. 369,016.

To all whom it may concern:

Be it known that I, WALTHER KIBY, a subject of the German Republic, residing at Noordwijk aan Zee, the Netherlands, have invented certain new and useful Improvements in the Construction of Subheated Regenerative Coke Ovens (for which I have filed application for a patent in Germany on Jan. 10, 1918), of which the following is a specification.

The present invention refers to subheated coke-ovens with vertical heating flues, each of which receives at its lower end gas from a burner and preheated air from a checker-work-chamber lying next to the burner-brick. Both gas and air are to be regulated from the passage-ways underneath the ovens.

According to the description and drawing of specification Serial No. 369,006, filed July 20 13, 1920, the air, which is admitted to each individual checker-work-chamber as well as the wasteheat, coming from each individual chamber, passes through a common opening, the size of which is regulated by a special 25 damper.

In ovens with a common main horizontal flue at the upper end of the vertical flues the difficulty arises, that the openings at the lower end of the checker-board-chambers, when they are regulated for a good distribution of the air will not be appropriately dimensioned for the even distribution of the waste heat over all the chambers. In this case an even preheating of the air is not 35 possible and thus an uneven heating of the total length of the oven-walls may be the result.

According to the present invention which relates to an improvement on that shown in my application Serial No. 369,006, the admission of the air to the checker-work-chambers and the outflow of the wasteheat from the checker-work-chambers is effected through separate channels which connect 45 with separate flues underneath. The connection for each chamber is regulated by a special damper and thus an even heating of all single flues is assured. The operating of the regulating dampers is likewise effected 50 from the subways and preferably one opening serves to attend at the same time one air and one waste-heat-damper.

Fig. 1 is a sectional view taken on three planes on lines parallel to the oven chamber.

Fig. 2 is a sectional view on the line *g*—*h* 55 of Fig. 1.

Fig. 3 is a horizontal section on lines *i*—*k*, *l*—*m* and *n*—*o* of Fig. 2.

Fig. 4 is a vertical sectional detail thru part of the oven structure on line *e*—*f*, of 60 Fig. 2.

Fig. 5 is an enlarged sectional detail of the lower part of Fig. 2.

Fig. 6 is a transverse detail section on line *n*—*o* of Fig. 5. 65

Fig. 7 is a detail section on line *p*—*q* of Fig. 6.

On the drawing is shown a regenerative-coke-oven with vertical heating flues and a main horizontal flue at their upper end. 70 Between the oven-chambers *a* are situated the oven walls with vertical heating flues *b* and *b*₁, which receive alternately heating gas from the burners *c* supplied from gas main *M* thru branch pipes *m*. The air for flues *b* is preheated in checker-work-chambers *d* and the air for flues *b*₁ in chambers *d*₁. For each oven and underneath the checker-work-chambers are arranged two flues, which are parted in two halves, flue *e* (*e*₁) serving only for the admission of the air and flue *f* (*f*₁) only for the outflow of the waste-heat.

Flues *e* and *e*₁ have at their outer ends air valves *v*, *v*', which are alternately opened 85 and closed while flues *f* and *f*₁ are each connected by means of reversing valves *w*, *w*' with a main stack flue *z*—*z*' on each side.

Each checker-work-chamber connects through an opening *g* with the air flue *e* 90 (*e*₁) and through an opening *h* with the wasteheat flue *f* (*f*₁), of which the former is regulated by a damper *i*, the latter by a damper *k*, both to be manipulated through an opening *l* from the subways. Dampers *i* 95 and *k* preferably consist of slide blocks which can be separately moved by a rod entering a hole in the bottom of each block, the rod being introduced through the opening *l* for this purpose. The size of openings *g* and *h* can thus be separately regulated.

It will be seen that by the right use of the various dampers an even heating of all the flues is assured.

Having now fully described my invention, 105 what I claim as new and desire to secure by Letters Patent is:

1. In a horizontal sub-heated regenerative

- coke oven provided with subways underneath the oven and with vertical heating flues and with a separate air preheating chamber for each flue, said ovens being 5 raised above said subways and the said chambers being connected to the lower end of each heating flue and situated between the floors of the oven chamber and the ceilings of the subways, the combination of a 10 sole flue for the distribution of air underneath each row of preheating chambers and another sole flue for the discharge of waste gases from said row of preheating chambers, both sole flues being connected to each preheating chamber and means for separately regulating the air supplied to and the waste gases discharged from each individual chamber.
2. In a horizontal sub-heated regenerative coke oven provided with subways underneath the oven and with vertical heating flues, the combination with said flues of a 20 separate air preheating chamber for each flue, the chambers being connected to the lower end of each heating flue and situated between the floor of the oven chamber and the ceiling of the subways, a sole flue for the distribution of air, said flue lying underneath each row of preheating chambers, another sole flue for the discharge of waste 25 gases, said flue also lying underneath said row of preheating chambers, both sole flues being connected to each preheating chamber, means for separately regulating the air supplied to and the waste gases discharged from each individual chamber, comprising a 30 valve for separately regulating the air supplied to each individual chamber and a separate and independent valve for separately regulating the waste gases discharged from each individual chamber, the ceiling being supplied with rows of openings, one opening 35 for each pair of air and waste gases valves, thru which the said pair of valves may be regulated.
3. In a horizontal sub-heated regenerative coke oven provided with subways underneath the oven and with vertical heating flues, the combination with said flues of a 40 separate air preheating chamber for each flue, the chambers being connected to the lower end of each heating flue and situated 45 between the floor of the oven chamber and the ceiling of the subways, a sole flue for the distribution of air, said flue lying underneath each row of preheating chambers, another sole flue for the discharge of waste 50 gases, said flue also lying underneath said row of preheating chambers, both sole flues being connected to each preheating chamber, and means for separately regulating the air supplied to and the waste gases discharged from each individual chamber, comprising a 55 valve for separately regulating the air supplied to each individual chamber and a separate and independent valve for separately regulating the waste gases discharged from each individual chamber.
4. In a horizontal sub-heated regenerative coke oven provided with subways underneath the oven and with vertical heating flues, the combination with said flues of a 60 separate air preheating chamber for each flue, the chambers being connected to the lower end of each heating flue and situated between the floor of the oven chamber and the ceiling of the subways, a sole flue for the distribution of air, said flue lying underneath each row of preheating chambers, another sole flue for the discharge of waste 65 gases, said flue also lying underneath said row of preheating chambers, both sole flues being connected to each preheating chamber, and means for separately regulating the air supplied to and the waste gases discharged from each individual chamber, comprising a 70 valve for separately regulating the air supplied to each individual chamber and a separate and independent valve for separately regulating the waste gases discharged from each individual chamber, the ceiling being supplied with rows of openings, one opening 75 for each pair of air and waste gases valves, thru which the said pair of valves may be regulated.

In testimony whereof I affix my signature. 80

WALTHER HIRY.
